UNITED STATES PATENT OFFICE

WILLIAM H. JOHNSTON, OF PROCTOR, MINNESOTA

ADJUSTABLE LINER

Application filed May 18, 1927. Serial No. 192,374.

The invention pertains to a locomotive underframe, and more particularly to an adjustable wedge disposed around the axle for the purpose of eliminating or taking up the lateral therein.

When a locomotive passes around curves, a heavy lateral pressure is exerted between the outside faces of the outside driving boxes and the faces of the hubs of the drivers. This lateral pressure causes a great deal of wear at the contact points which causes an excess clearance between these parts known as "lateral". This lateral in common practice is usually taken up by a removable liner interposed between the drivers and the journal boxes, which liner may be renewed as it is worn thin.

It is therefore an object of this invention to provide a novel means adapted to be interposed between parts in the underframe of the locomotive to prevent too great a play between the hubs of the drivers and the faces of the driving boxes.

Another object is to provide a novel, simple and inexpensive means to be disposed between parts of the locomotive underframe to take up axle lateral.

A further object is to provide an effective means which may take the form of a tapered wedge provided with actuating means to eliminate play between the locomotive axle and the underframe.

A more specific object is to provide a substantially U-shaped wedge adapted to straddle the axle and to provide a simple and accessible actuating and locking means on said U-shaped member for the purpose of eliminating axle lateral and holding the bearings and wheels in correct and efficient working position.

With these and various other objects in view, the invention may consist of certain novel features of construction and operation as will be more fully described and particularly pointed out in the specification, drawings and claims appended hereto.

In the drawings, wherein like reference characters are used to designate like parts—

Figure 1 is an elevation taken transversely of the locomotive, showing the preferred

form of lateral eliminating means applied to the axle;

Figure 2 is a detailed perspective of the tapered wedge; and

Figure 3 is a modification of Figure 1, 55 wherein the wedges are replaced by shims.

The usual locomotive drivers 1, which are keyed or otherwise positioned on the axle 2, are carried by the engine underframe 3 through the medium of suitable bearings 4. Bolted or otherwise secured, as at 16, to the bearings 4 are suitable filler blocks 5, which are adapted to be secured by suitable means 18 to the liners 7. Fastened between these liners and located substantially on the center line of the engine is a suitable thrust bearing 6 having suitable adjusting means 17 provided thereon. Between the filler block and the liner in the preferred form, is provided the tapered wedge 8, as shown in Figure 2, the tapered face of which operatively cooperates with a correspondingly tapered face on the filler block 5. This wedge is provided with a substantially U-shaped slot 9 which is adapted to be fitted around the axle 2, and suitable lugs or shoulders 10 on either side of the liner, which contact the sides of the filler block to prevent the wedge from working out of position.

In view of the fastening bolts 18 provided between the filler block and the liner, there are suitable slots 11 of a number corresponding to the number of bolts, which allow the wedge to be adjusted vertically. At the top of the wedge, a shoulder 12 is provided having a suitable slot 13 which is adapted to carry suitable locking and adjusting means 19 which are shown as a nut and bolt arrangement, the bolt being threaded in a suitable hole provided therefor in the top of the filler block. As already described, the wedge is of tapered form, having its widest part 14 disposed at the top and gradually tapering to a thin part 15 disposed on either side of the axle slot 9. The shoulders 10 serve as stop members to prevent rotative or sidewise movement of the wedges by cooperating with the filler blocks 5 and also serve as positioning members or guides in conjunction with the guiding slots 11.

In the modification, illustrated in Fig. 3, the wedge 8 is replaced by a shim 8' which may be substantially the same shape as the wedge, having the axle slot and holes in way of the fastening bolts 18, but it will be seen that this shim 8' is of constant width and the holes may be round to perfectly fit the fastening means 18. With the wedge, it will be seen that any predetermined clearance between the faces of the hub of the driver can be provided and maintained, any looseness which may appear due to wear being taken up by means of the positioning bolts 19 provided for the top of the wedge. This provides a very simple take-up and one which is effective as well as positive. In the application of the shims, it is of course understood that new shims have to be provided or additional shims must be added for each amount of lateral desired to be eliminated.

It is to be understood that I do not wish to be limited by the exact embodiment of the device shown, which is merely by way of illustration and not limitation, as various and other forms of the device will of course be apparent to those skilled in the art without departure from the spirit of the invention or the scope of the claims.

I claim:

- 30 1. In a device of the character described, the combination of a locomotive frame, a filler block, a thrust bearing, and a U-shaped member adapted to be interposed between the filler block and thrust bearing to eliminate the axle lateral.
- 35 2. In a device of the character described, the combination of a car axle, and a U-shaped member adapted to cooperate with said axle to take up the lateral therein, said member comprising a vertical travel limiting means, and means on the U-shaped member for actuating said member.
- 40 3. In a device of the character described, the combination with a locomotive under-frame, an axle, a journal box for said axle, a filler block, a liner, and means adapted to be disposed between the liner and the filler block to eliminate axle lateral.
- 45 4. In a device of the character described, the combination with a locomotive frame, a journal box, an axle, a filler block fastened to said journal box, an adjustable thrust bearing, a liner, means connecting said liner to said filler block; and a U-shaped member interposed between said liner and filler block for the purpose set forth.
- 50 5. In a device of the character described, the combination with a locomotive frame, a journal box, an axle, a filler block fastened to said journal box, an adjustable thrust bearing, a liner, means connecting said liner to said filler block, and a U-shaped member interposed between said liner and filler block and straddling the axle and provided with slots permitting relative movement between the

connecting means and the U-shaped member, said U-shaped member having means cooperating with the filler block to cause wedging action of said U-shaped member.

6. In a device of the character described, the combination with a locomotive frame, a journal box, an axle, a filler block fastened to said journal box, an adjustable thrust bearing, a liner, means connecting said liner to said filler block, and a U-shaped member interposed between said liner and filler block for the purpose set forth, said U-shaped member having a taper corresponding to the sloping face of the filler block and straddling the axle and provided with slots permitting relative movement between the connecting means and the U-shaped member, said U-shaped member having means cooperating with the filler block to cause wedging action of said U-shaped member.

7. As an article of manufacture, a U-shaped member having means for effecting movement of said member, said member being provided with elongated apertures therein for permitting limited movement thereof.

8. As an article of manufacture, a U-shaped member having stops thereon, means including a lug having an open slot for effecting movement of said member, said member being provided with elongated apertures therein for permitting limited movement thereof.

9. As an article of manufacture, a wedge shaped member having means including a lug having an open slot for effecting movement of said member, said member being provided with elongated apertures therein for permitting limited movement thereof.

10. As an article of manufacture, a wedge shaped member having stops thereon, means including a lug having an open slot for effecting movement of said member, said member being provided with elongated apertures therein for permitting limited movement thereof.

11. As an article of manufacture a liner comprising a wedge shaped member having guiding shoulders thereon, said member having an axle receiving opening, means formed integral therewith for effecting movement of said member and means in addition to said shoulders for guiding said member during movement thereof.

12. As an article of manufacture a liner comprising a U-shaped member having guiding shoulders thereon, said member having an axle receiving opening, means formed integral with the member for effecting the movement of said member and means in addition to said shoulders for guiding said member during movement thereof.

13. As an article of manufacture a liner comprising a wedge-shaped member having means formed integral therewith for effecting movement of said member, said member being

provided with elongated apertures therein for permitting limited movement thereof.

14. As an article of manufacture, a liner comprising a U-shaped member having guiding shoulders thereon and being provided with elongated apertures therein permitting limited movement thereof.

Signed at Proctor, Minnesota, this 3rd day of May, 1927.

10 WILLIAM H. JOHNSTON.
